UNITED STATES PATENT OFFICE.

HUGH A. SMITH, OF HOPEWELL, NEW JERSEY, ASSIGNOR TO THE STANDARD METER COMPANY, OF HOPEWELL, NEW JERSEY, A CORPORATION OF NEW JERSEY.

PREPAYMENT GAS-METER.

1,036,361.

Specification of Letters Patent. Patented Aug. 20, 1912.

Application filed April 13, 1909. Serial No. 489,703.

To all whom it may concern:

Be it known that I, HUGH A. SMITH, a citizen of the United States, residing in Hopewell, New Jersey, have invented certain Improvements in Prepayment Gas-Meters, of which the following is a specification.

My invention relates to certain improvements in gas meters of the prepayment type, in which a coin is deposited and the mechanism manipulated so as to allow the meter to run until a given amount of gas is registered, when it is automatically shut off until another coin is deposited.

One object of my invention is to so construct the operating parts that they will work accurately and not be liable to get out of order, and a further object is to mount the prepayment device on the outside of the meter casing and couple it to the meter mechanism so that there will be no leakage of gas. And a still further object is to so attach the inclosing casing and cash receptacle as to make them readily detachable, but, when in place, secure against tampering. These objects I attain in the following manner, reference being had to the accompanying drawings, in which:

Figure 1, is a front view of a gas meter illustrating my improved prepayment device; Fig. 2, is a sectional plan view on the line 2—2, Fig. 3; Fig. 3, is a vertical sectional view on the line 3—3, Fig. 2; Fig. 4 is a transverse sectional view on the line 4—4, Fig. 2; Fig. 5, is an end view showing the gearing; Fig. 6, is a detached perspective view of the back plate; Fig. 7, is a detached perspective view of the cover; Fig. 8, is a detached perspective view of the coin drawer; Fig. 9, is a perspective view of the two rods which secure the casing to the back plate; and Figs. 10, 11 and 12, are perspective views of details of the invention.

Referring to Fig. 1, A is the casing of an ordinary gas meter and B is the prepayment device located at one side of the meter casing. C is the valve box in which is a valve actuated by the prepayment device to cut off the supply of gas when the amount of gas is consumed for which prepayment was made. The valve stem *c* has a slotted arm *c'*, Fig. 12, in which a pin travels which is carried by the prepayment device. D is a shaft having on its outer end a long pinion *D'* and mounted on this shaft within the meter casing is a worm wheel *d* actuated by

a worm *d'* on the shaft *D²* driven by a worm and worm gearing from the main shaft *D³* of the meter. The shaft *D* extends through a stuffing box *a* in the casing of the meter, thus preventing any escape of gas from the meter casing in the event of a leakage at any of the joints within the meter casing. The frame of the prepayment device consists of a back plate *B'* and a front plate *B²* connected together by suitable rods *b*, so as to make a rigid frame. This frame is enclosed within a casing *E* as described in detail hereafter. In this casing, however, is a chute *e* through which the coin is inserted and above the chute in the present instance is a glazed opening *e'* through which the indicating plate *b'* is visible. *F* is a shaft having an enlarged portion *f* and slotted at *f'* for the reception of the coin, Fig. 10, and on this shaft is a pin *f²* adapted to strike against stops *b²*, *b³* on the back plate *B'*. The shaft is in a direct line with the chute *e* so that when the coin is placed in the chute it will slide into the slot in the shaft and be in position so that when the shaft is turned by the handle *f* it will make a half-turn, carrying the coin with it, and the coin will actuate a star wheel *G'* on the shaft *G*; the edge of the coin entering one of the notches *g* in the star wheel and turning the star wheel a given distance.

Pivoted at *h* to a stud on the frame of the machine is a dog *H* having a pin *h'* which enters one of the notches in the star wheel and locks it after the coin has actuated the wheel, and this dog has an arm *h²* which is in the path of the coin as it is turned to actuate the star wheel, so that the coin first lifts the dog and its pin out of the engagement with the star wheel, and immediately the coin engages the star wheel and turns it the proper distance. As soon as the coin passes the arm of the dog the pin will drop into another slot, owing to the weight of the dog, locking the star wheel and its shaft. On the end of the shaft *G* is a gear wheel *g'*, Fig. 5, which meshes with an intermediate pinion *i* on a stud *I* and connected to this pinion is a gear wheel *g''* which meshes with a pinion *k* on a screw shaft *K* and adapted to travel on this screw shaft is a gear wheel *M* which meshes with the long pinion *D'* on the shaft *D* which extends into the casing of the meter and is geared to the driving shaft *D³*, as explained above. The hub *m* of the gear wheel *M* is

grooved to receive a bar N, Fig. 11, which is adapted to a rod b^4 mounted in the casing, and carried by this bar is an indicator hand n which travels in front of the indicator plate b' . The bar extends rearwardly and has a pin n' which enters the slot in the arm c' carried by the valve spindle c mounted in the valve box C. A projecting pin b^5 in the present instance acts as a guide for the inner end of the bar N. In order to make the gearing interchangeable so that coins of different values may be used, I preferably mount the stud I on a carrier I' pivoted to the shaft K, and this carrier has a segmental slot through which passes a locking screw i^2 which will lock the carrier in any position to which it is adjusted, and the gears g' and i can be removed and gears of different diameters substituted therefor; 10 the gear g' in the present instance having a square opening adapted to fit over the squared end of the shaft G and a pivoted spring plate g^2 holds the gear in place. Thus by changing the two gears more or 15 less movement can be given to the screw shaft K. Thus it will be seen by the above construction that when a coin is inserted in the chute it slides into the slot in the shaft F and by turning the shaft a half turn it 20 will actuate the star wheel and turn it a given distance, this motion will be transmitted through the gearing to the screw shaft K, which will move the gear wheel M and the bar carried thereby a given distance 25 in one direction, and the pin on the bar will open the valve in the valve casing C so that 30 a supply of gas can pass through the meter. At the same time the hand will indicate the 35 amount of gas which is paid for.

40 As the gas is consumed the shaft D is driven by the main shaft of the meter and as this shaft is geared through its long pinion D' to the gear wheel M on the screw shaft K it will move the said gear wheel 45 and its bar N along the shaft in the opposite direction, gradually moving the indicator, at the same time moving the pin toward the cutting off point to close the valve in the valve box C. In this meter the valve 50 will not close abruptly, but before the valve entirely cuts off the gas it will reduce the opening so as to indicate to the consumer that the gas will be cut off without an additional coin is placed in the prepayment device.

55 In order to properly inclose the operating mechanism of the prepayment device so that when necessary access can be had to it, I provide a detachable casing E, clearly shown in Fig. 7, in which is the chute e and a glazed opening e' mentioned above, and this casing fits over the entire mechanism and is deep enough to contain the money drawer at

the base. The lower end is open and has inturned flanges e^2 to which is adapted the 65 slide P, illustrated in Fig. 8, on which is mounted the money receptacle P'. The slide P has the edges p upturned so as to fit on the outside of the casing and has a plate p' which overlaps the flanges e^2 , so as to form 70 a secure joint between the plate and the slide. The slide has a back plate P^2 provided with flanges p^2 adapted to extend on the outside of the casing E, and carried by this back plate is a lock S having a bolt s 75 adapted to be projected on the inside of the casing E, so as to prevent the withdrawal of the slide P without first operating the lock. The upper portion of the money receptacle P' is flared at p^3 so as to fit under the mechanism and direct the coin into the receptacle P'.

On the back plate B' of the prepayment mechanism are perforated lugs t and on the interior portion of the casing near the back 85 plate are projecting perforated lugs v . When the casing is placed in position the openings in the lugs t and v are in line and the rods T can be inserted from the bottom through the several openings, locking the 90 casing firmly to the back plate. The rods T are preferably turned at right angles, as illustrated in Fig. 9, and have eyes t' which can be turned over the pin u on the back plate and held in place by an ordinary wired 95 seal, the wire passing through an opening in the pin u , as illustrated by dotted lines in Fig. 4. Thus it is impossible to remove the casing E without disturbing the seal and access cannot be had to this seal without 100 first removing the slide on which the money receptacle is mounted. By this construction a very substantial and easily detached casing is provided which cannot be maliciously broken into without destroying some 105 part of the apparatus.

I claim:—

The combination of a casing, a shaft within said casing having a long pinion, mechanism capable of actuating said shaft, a screw 110 shaft, a gear adapted to travel on the screw shaft and meshing with the long pinion, a bar engaging the hub of the gear, a gas-controlling valve actuated by the bar, a shaft having a star-wheel thereon, and geared to 115 the screw shaft, a pawl engaging the star-wheel, a pawl-tripping structure; and a rod mounted to removably support said pawl-tripping structure.

In testimony whereof, I have signed my 120 name to this specification, in the presence of two subscribing witnesses.

HUGH A. SMITH.
